UNITED STATES PATENT OFFICE.

CORNELL FLAGSTAD AND OSCAR A. FLAGSTAD, OF MINNEAPOLIS, MINNESOTA, AS
SIGNORS OF NINETY-FIVE PER CENT TO THE FOLDING CRATE & BOX COMPANY, OF
MINNEAPOLIS, MINNESOTA, A CORPORATION OF MINNESOTA.

COLLAPSIBLE CRATE.

Application filed September 8, 1924. Serial No. 736,535.

This invention relates to collapsible carriers and the main object is to provide a simple, practical and efficient crate in which side and end sections are hingedly secured to a hollow base so as to be foldable thereinto, and in which a cover section has means whereby it may be detachably secured, either to the vertical sections when the crate is set up, or to the base section when the 10 crate is collapsed so as to lock all the parts in a closely nested condition. A further object is to provide means of a novel nature for hingedly securing and detachably connecting the various crate members. A further 15 object is to provide improved means for bracing various objects within the crate. Still further and more specific objects will be disclosed in the course of the following specification, reference being had to the accompanying drawings, in which:

Fig. 1 is a side elevation of the crate.

Fig. 2 is a top or plan view of the crate shown in Fig. 1.

Fig. 3 is an enlarged detail sectional view 25 on the line 3—3 in Fig. 2.

Fig. 4 is an enlarged detail sectional view on the line 4—4 in Fig. 2.

Fig. 5 is an enlarged perspective view of a preferred type of hinge which is used in 30 the crate.

Fig. 6 is a detail sectional view of one corner of a crate showing a modification in the corner locking device.

Fig. 7 is a fractional detail view showing a modification in the device for locking 35 the cover section in place.

Fig. 8 is a section on the line 8—8 in Fig. 7.

Fig. 9 is an enlarged section similar to 40 Fig. 8, but showing a modification thereover.

Fig. 10 and Fig. 11 show further modifications of the cover locking device.

Fig. 12 is an enlarged detail section on 45 the line 12—12 in Fig. 11.

Fig. 13 is a perspective detail view of a corner locking device.

Fig. 14 is a sectional elevation through the 50 crate showing certain bracing features.

Fig. 15 is an enlarged detail section on the line 15—15 in Fig. 14.

Fig. 16 is a perspective view of the member 73—74 shown in section in Fig. 14.

Fig. 17 is an elevation of one corner por-

tion of a crate illustrating a modification in 55 the bracing structure.

Fig. 18 is a plan view of the member K shown in Fig. 17.

Fig. 19 is a sectional elevation of the upper portion of a crate showing a further 60 modification in the bracing construction.

Fig. 20 is an enlarged detail section through the crate, as on the line 20—20 in Fig. 19.

Reference will now be made to the drawings by reference characters, like characters referring to like parts throughout the various figures.

The crate consists primarily of a shallow base A, having a bottom 21 and an upstanding rim 22; a pair of end sections B, a pair of side sections C, and a cover D. The end and side sections are hingedly secured to the base so as to be foldable thereinto when the crate is collapsed, and the cover section is 70 arranged and constructed so that it may be secured either to the vertical sections, when the crate is set up, or to the base when the crate is collapsed. The construction thus far described is also shown in a general way 75 in our Patent No. 1,485,973 which issued March 4th, 1924, for a folding box or crate, and are therefore not here claimed as being broadly new.

The end sections B consist of vertical 80 slats 23 and horizontal slats 24 and 25. The side sections C consist of vertical slats 26 and horizontal slats 27 and 28; and the top section D consists of longitudinal slats 29 secured to transverse slats 30, and braced by 85 diagonal slats 31. The lower ends of the vertical slats of the side and end sections are secured to the base by hinges E, (see Figs. 1, 5 and 14), in such a manner that their pintles will be offset, vertically, to permit 90 the sections to be folded into the base, one on top of the other.

Each hinge member E, as shown in Fig. 5, consists of an angularly formed sheet metal plate, in each leg of which is inwardly 95 struck a channel portion 32, having pintle perforations 33, for a pintle as 34. The pintle may consist merely of a nail whose pointed end is bent around, as shown, to prevent it from falling out. The hinge 100 member E¹, of which two are of course used for each vertical section, consists of a substantially U-shaped strap iron member 105

which is nailed over the lower end of the slat 26 (or 23), and is cut out so that it may operate at the sides of the portion 32, a tongue 35 being struck up to form a seat for the slat and to make the member E¹ very rigid with the slat.

The means employed to detachably connect the side and end sections together in set up position is shown in Figs. 2, 3 and 4, and with 10 modifications in Figs. 6 and 13, and will now be described.

Referring first to Figs. 2, 3 and 4, it will be seen that a pair of heavy wire locking members F are rotatably mounted, one in 15 each of the end sections B, and are provided with hooks 36 at their ends adapted to engage receiving brackets 37 on the side sections C. The members F are also provided with V-shaped bail portions 38, which, when 20 the hooks 36 are engaged in brackets 37, are substantially horizontal and lie directly under the cover D. Thus it will be seen that while the hooks 36 positively lock the crate corners rigid they cannot be disengaged unless 25 the bail portions 38 are swung up, and this cannot occur while the cover is locked in place.

In Fig. 6 the section B is provided with a hook 39 which, as the section is swung up 30 into place, engages in a bracket member 40, on the section C, in such a manner that both sections are secured together and cannot swing out past a vertical position. The hook may be provided with a friction lip 41 so that 35 it will not be so easily displaced. As the cover D fits between the upper ends of the side and end sections, there is of course no necessity for otherwise locking those sections against inward movement when the crate is 40 set up. In the corner lock modification shown in Fig. 13 a pair of hinge butts 42 are secured one on each section and are connected by a removable pin 43, which may also of course be held in place in a releasable manner 45 by the crate cover D.

The cover is detachably secured in place by means, the preferred form of which is illustrated in Figs. 1, 2, 3 and 4, while modifications thereof are illustrated in Figs. 7 50 to 12, inclusive. In any event one end of the cover is provided with a pair of fixed fingers 44 which are arranged to engage corresponding apertures 45 in one end section, or apertures 46 in one end of the base. The 55 other end of the crate cover is provided with a retractable bolt G, arranged to releasably engage in apertures 47 (or 48) in the opposite end of the crate.

The bolt G (Figs. 2, 3) is slidably secured 60 in the member 29, and is offset so as to conceal a compression spring 48 between itself and the member 30. The top of the bolt is flush with the slat 29, but the latter has a depression 49 so that the finger may be used 65 (as shown in dotted lines in Fig. 3) to with-

draw the bolt from the end section. The bolt G¹ (Figs. 7 and 8) is slidably mounted in the cover, and has a convenient finger lip 50. The spring 51, in this case, merely engages the bolt to frictionally hold it in either 70 open or closed position. The bolt G² (Fig. 9) also has a friction spring 52, but a leaf 53 is interposed between the member G² and 75 52, and has a lip to engage the rear end of the bolt in such a manner that the lip must be depressed before the bolt can be pulled back. The bolt G³ (Fig. 10) is slidably secured between the members 29—30, and has an integral finger 54 which carries the spring 55 which coacts with small shoulders 56 to hold the bolt extended. The bolt 80 G⁴ (Figs. 11 and 12) is an L-shaped member which is releasably held in its extended position by a hinge like device 57—58. The member 58 is rigidly secured to the slat 29, while the member 57 swings from the member 58 and is spring actuated in a direction to hold the bolt G⁴ extended or locked. When the member 57 is manually raised the bolt may be retracted to release the cover, and if withdrawn far enough may hold the member 57 85 back adjacent to the member 58, as indicated by dotted lines in Fig. 12.

The crate may of course be used for any purpose desired. In the present instance, 90 however, it has been especially designed for the purpose of shipping automobile radiators, and with this end in view various means are shown for rigidly securing the radiators within the crate in such a manner that they 95 will not only be firmly retained in place, but may easily and quickly be secured in the crate without the use of nails, bolts or such similar devices as are ordinarily used in non-collapsible shipping carriers.

The crate shown in Figs. 1 and 2 is equipped to receive two radiators H and J of the well known Ford type. These radiators, when detached from the car, are provided with laterally extending flanges 59 100 having angular lips 60. The base A is provided with a pair of blocks 61, and the crate is further provided with a pair of co-operating strips 62, which are offset from the blocks 61 so that the radiator can be moved 105 angularly with the flanges 59 into bracing positions between the members 61—62, as shown in Fig. 1. The members 62 have inclined faces 63 so that when the radiator H is lifted out the lips 60 will not positively 110 stop against 62 and be bruised or broken, but will move the radiator slightly forward so that it can be cleared. The radiators H and J are reversed, as shown in Fig. 1, and are held apart by a pair of blocks 64. The flanges 59 of the radiator J now drop down 115 between the blocks 65 and 66, on the side sections, the lip 60 stopping on the block 66. Now, when the cover D is locked in place it will obviously prevent any vertical 120

movements of the radiators in the crate, while the stops 61, 62, 65 and 66 will prevent any longitudinal play.

In the modification shown in Figs. 17 and 18 the above mentioned stops are substituted by pairs of strips 67 which are rigidly secured to the side sections. These strips are spaced apart to form a channel to slidably receive the radiator members 59, 60. A spacing member K is now employed and consists of a transverse slat 68, which is utilized to space the radiators from each other, and a pair of depending legs 69, which drop between the members 59 and 67 to hold the slat 68 in an upright position and also to brace or make more rigid the lower radiator.

In Figs. 14, 15 and 16 further modifications in the spacing and horizontal bracing are illustrated. Thus, 70 designates a partly channeled slat, two of which support a transverse brace 71, on which is supported one end of the radiator. The other end may be supported on a somewhat similar brace 72, which guides between strips 73, and is preferably provided with face plates 74 which give a greater bearing surface on the crates and thus prevent injury to the honeycomb tubes of the radiator.

In larger types of crates it is often desirable to set the radiators up vertically in the crate, and in this event it is also necessary to space them from each other to prevent injury. This spacing may be accomplished merely by a series of cross slats 75 slidably retained between guides 76 (Fig. 14). A further improved method, however, is shown in Figs. 19 and 20, and consists in spacing the slats 75, horizontally, by blocks 77, so that the horizontal pressure from each radiator will not be imparted to the radiators in front or behind it, but will be taken up directly by the crate. In this event also, it is desirable to spring hinge one of the upper guide members 76^a, as at 78, so that the strips 75 may be conveniently withdrawn or inserted, by raising the member 76 as indicated by dotted lines in Fig. 20.

It is understood that various modifica-

tions may be made in the general design and structural details of the crate construction as herein illustrated and described, provided, however, that such modifications come within the spirit and scope of the appended claims. Having now therefore fully shown and described our invention, what we claim to be new and desire to protect by United States Letters Patent is:

1. A collapsible crate of the character described consisting of a base, side and end sections hingedly secured to the base and foldable thereto when the crate is collapsed, a detachable cover, means for releasably securing the side and end sections together when in a set up position, said means comprising members turnably carried by opposite of said sections for locking engagement with the other of said sections at the corners of the crate, and means operative by placing the cover in position upon the crate for locking said securing means by engaging said members to prevent them from turning.

2. The combination with a crate having a base and side and end sections hingedly secured thereto, of corner locking devices for releasably locking the side and end sections together in set up positions, said devices being each rotatably secured and releasable by upward swinging movements of certain parts thereof, a cover adapted to be detachably secured upon the crate, said cover being downwardly engageable against said locking devices to prevent such upward swinging movements of said parts while the cover is in position.

3. The combination with a folding crate having a hollow base and inwardly folding side and end sections, of right angularly shaped hinge plates secured in each corner of the base as a brace therefore, each leg of said hinge plates having an inwardly struck channel portion having transversely arranged pintle holes, the holes in the respective channel portions being offset vertically.

In testimony whereof we affix our signatures.

CORNELL FLAGSTAD.
OSCAR A. FLAGSTAD.
